CIRCUIT BREAKER

Wolfgang E. Schwarzmann, Longmeadow, Mass.,
assignor to United American Bosch Corporation,
Springfield, Mass., a corporation of New York

Application September 16, 1932, Serial No. 633,412

3 Claims. (Cl. 200—30)

My invention relates to improvements in devices for making and breaking electrical circuits; and particularly to a circuit breaker for the electrical ignition circuits of internal combustion engines.

5 It is an object of the invention to provide a circuit breaker for an ignition circuit of simple but efficient construction with the parts mounted to facilitate adjustment and capable of embodiment to include one or more sets of contact points.

10 The nature and scope of the invention is fully set forth in the ensuing description, and the novel features are pointed out in the appended claims. But the disclosure is, of course, explanatory only and changes may be made without departing from 15 the principle of the invention or exceeding the breadth of the terms in which the claims are expressed.

On the drawing:

20 Fig. 1 is a top plan of a circuit breaker according to this invention; and

Fig. 2 is a side view thereof partly in section.

On the drawing the same numerals identify the same parts throughout.

25 In the form illustrated herein the circuit breaker comprises a base or mounting plate 1 on which is pivotally mounted a pair of interrupter levers 2, each carrying a movable contact point 3 which cooperates with a fixed contact point 4. Attached to each interrupter lever 2 is a bent leaf spring 5 which is anchored at its opposite end to a supporting post 6 rigidly secured to the base 1. The circuit breaker is thus shown as embracing two interrupter levers with cooperating fixed electrodes, but obviously one such interrupter lever and its cooperating contact may be employed or more than two may be mounted on the base 1 according to requirements of design. The interrupter is especially adapted for use with airplane engines and it may be used on engines of other types as well.

30 On the base 1, further, is mounted a pair of condensers 7, one of which is to be bridged across each pair of contacts 3 and 4. These condensers have their insulated poles connected by metallic straps 8 to the posts 6; the opposite pole of the condenser being grounded on the metallic base 1, each of these straps and the spring 5 of the associated pair of interrupter contacts being anchored to the posts 6 by means of a screw or other fastening device 9. The posts 6 are rigidly attached to the base 1 by rivets 10 passing through openings in the base into suitable bores in the bottom of the posts 6. The rivets 10 are of smaller diameter than these openings and are surrounded

5 by insulating sleeves 11 within the openings; while insulating washers 12 prevent contact between the bottoms of the posts and the heads of the rivets with the base plate 1. Cooperating with these insulating washers 12, the posts 6 have reinforcing plates 13 at the lower ends thereof and extending laterally, as shown in Fig. 1, to brace said posts when rivets 10 are tightened. The posts 6 although of metal are, therefore, electrically disconnected from the plate 1 and are 10 securely attached to the plate; and each of these posts forms a suitable fulcrum for the spring 5 secured to it by means of the screw 9.

15 Each interrupter lever 2, which is of insulation, is mounted upon the upper end of a metallic post 14, which is affixed to the base 1 by reducing the lower end thereof, passing it through an opening in the base and then riveting the lower end over to make it engage the opening firmly. The upper ends of these posts may be reduced as shown 20 at 15; these reduced extremities passing through openings in the levers 2; and these levers can therefore turn about the upper ends of the posts 14 as pivots or journals to move the contact points 3 into or out of engagement with the contact 25 points 4.

Each fixed contact 4 is mounted upon the upright part of an L-shaped post or bracket 16, the horizontal section 17 of which rests upon the base plate 1. This section has slots 18 and 19 therein 30 at right angles to each other. Screws 20 pass through the slots 18 and additional screws 21 may pass through the slots 19 into threaded openings formed in the plate 1; so that these brackets 16 can be adjusted as required to keep the contacts 35 4 in correct position. Each of the movable contacts 3 is affixed to a metallic strip 22, these strips partly enveloping the insulating portions of the circuit breaker levers 2 on both sides of the pivoted end thereof; while the extremities 40 of these strips adjacent the central opening 24 of the circuit breaker are bent or curled over as shown at 23. When this circuit breaker is mounted in operative position a shaft, not shown, will pass through the central opening 24 and carry 45 on this end a cam which will engage the ends 23 of the strips 22 periodically to move the circuit breaker levers and separate the contacts 3 and 4. As the cam passes the curved over ends 23, the springs 5 will cause the contacts 3 and 4 to re- 50 engage each other.

To hold the condensers 7 in place on the base 1, the base has upright projections 25, preferably integral therewith, and to these projections are secured clamps 26 which encircle the condensers 55

and are attached to the projections 25 by screws 9 similar to those engaging the posts 6.

The circuit breaker levers 2 rest upon shoulders 27 formed by the reduced upper ends 15 of 5 the posts 14 and are prevented from becoming displaced by cotter pins 28 and washers 29.

In practice the metallic brackets 16 are in electrical connection with the base 1, but the movable contact points 3 which are carried by the 10 insulating bodies of the breaker levers 2 are in electrical connection with the posts 6 only. These posts are insulated from the base by the sleeves 11 and washers 12. The posts 6 are therefore provided with bores 30 passing through the same 15 from side to side near the upper ends; and in the outer ends of these posts are threaded openings to receive screws 31, the inner ends 32 of which enter the bores 30 and engage the ends of the electrical conductors of the supply circuit to hold these conductors fast. Current can thus 20 flow to each of the posts 6 and through the springs 5 and strips 22 to the movable contacts 3 and thence by way of the fixed contacts 4 to ground. Hence whenever the levers 2 are actuated to separate the contacts 3 and 4 the circuit 25 is broken. The condensers are each in parallel with one pair of contacts 3 and 4 because the insulated pole thereof is united to the associated posts 6 through the conductor 8 and the other pole, like the brackets 16, is electrically connected to the supporting plate 1.

With this construction, the circuits connected to the two pairs of contacts are opened in turn, when the interrupter is mounted in operative position and the ends 23 of the strips 22 are engaged by the cam on the shaft in the opening 24. The base 1 can of course be shifted to give the required angular adjustment when the instant of ignition is to be advanced or retarded.

40 The entire construction is very simple and ef-

ficient and comparatively inexpensive to produce and by shifting the brackets 16, when the screws 18 and 19 have been loosened, these brackets can be given the correct positions for proper engagement of the contacts 3 and 4.

Having described the invention, what is claimed is:

1. A circuit breaker comprising a disc, an upright condenser attached to said disc, the latter having a bent-up projection and a clamp surrounding the condenser and secured to said projection. 10

2. A circuit breaker comprising a disc, a fixed and a movable contact on said disc, an upright condenser on said disc, the latter having a bent-up projection, a clamp surrounding the condenser and secured to the projection, a metallic post on said disc between said contact and said condenser, a spring attached at one end to the post and extending in one direction and connected to the 20 movable contact and a conductor extending in the opposite direction and uniting said post to said condenser.

3. A circuit breaker comprising a disc, a post thereon in metallic connection therewith, an interrupter lever of insulation pivoted on said post, a metallic strip carried by said lever having a contact on one end, the other end being bent-over, a post attached to said disc but insulated therefrom, means on said last-named post for securing a conductor thereto, a spring attached to the lever and extending in one direction and to the last-named post, an upright condenser on the disc, the latter having a bent-up projection, a clamp surrounding the condenser and secured to said projection, said post being disposed between the condenser and the lever and a connection extending in the opposite direction from said last-named post to said condenser. 25 30 35
